UNITED STATES PATENT OFFICE.

FRIEDRICH C. LORENZ, OF MILWAUKEE, WISCONSIN.

DESIGN FOR A CHILD'S SLED.

SPECIFICATION forming part of Design No. 16,083, dated May 12, 1885.

Application filed April 13, 1885. Term of patent 7 years.

To all whom it may concern:

Be it known that I, FRIEDRICH C. LORENZ, a citizen of the United States, residing at Milwaukee, in the county of Milwaukee and State 5 of Wisconsin, have invented and produced a new and original Design for Children's Sleds, of which the following is a specification, reference being had therein to the accompanying drawing, which is a perspective view illustrating the design of my sled.

The shape of the runners A A is substantially square in cross-section, and they are horizontal for the greater part of their length, curving upward at their front ends, a a. The 15 body of the sled is in the shape of a horse, B, the four legs of which, b b b b, rest on the runners, the hoofs of the fore legs being located at the front termination of the horizontal part of the runners, just behind the beginning of 20 their upward bend. Between the knees of the rear legs there extends a rod, C, which is round in cross-section. The horse has a flowing tail, D, mane E, and imitation of a bridling

rein, F, with the imitation of a bridle, f f, on the head G. 25

Having thus described and illustrated my new and original design, I claim—

1. The design for a child's sled, the same consisting of two runners having superimposed thereon the figure of a horse, the four legs of 30 which figure rest upon the two runners, as shown and described.

2. A design for a child's sled, consisting of the horizontal runners A A, turned up in front, as at a a, and the body B, in the shape of a 35 horse, the legs b b b resting on the runners, and having a flowing tail, D, mane E, head G, and imitation of a bridle, F f f, as shown and described.

In testimony whereof I affix my signature in 40 presence of two witnesses.

FRIEDRICH CH. LORENZ.
